(57) **CLAIM**

The ornamental design for a tire tread, as shown and described.

DESCRIPTION

FIG. 1 is a perspective view of a tire tread of the present application;

FIG. 2 is a front view thereof;

FIG. 3 is side view thereof;

FIG. 4 is an enlarged partial perspective view thereof;

FIG. 5 is an enlarged partial front view thereof; and,

FIG. 6 is an enlarged partial side view thereof.

The region between the inner bead and the sidewall (identified by and including the broken lines) depicts subject matter that forms no part of the claimed tire tread design, and is included for the purpose of illustrating the full tire. The tread pattern is understood to repeat throughout the circumference of the tire. The other side view is identical to the illustrated side view of FIGS. 3 and 6.
